UNITED STATES PATENT OFFICE.

WILL C. NEAHR, OF DENVER, COLORADO, ASSIGNOR TO THE PROTECTIVE SIGNAL MANUFACTURING COMPANY, OF DENVER, COLORADO, A CORPORATION OF COLORADO.

ELECTROMAGNETIC DEVICE.

1,241,139.

Specification of Letters Patent. Patented Sept. 25, 1917.

Application filed November 14, 1916. Serial No. 131,836.

To all whom it may concern:

Be it known that I, WILL C. NEAHR, a citizen of the United States, residing at Denver, in the county of Denver and State of Colorado, have invented certain new and useful Improvements in Electromagnet Devices, of which the following is a specification.

The present invention relates to electromagnetic devices, and more specifically to improvements in the mechanism disclosed in my co-pending application, Serial No. 29,751.

The primary object is to provide a simple, compact, and thoroughly practical structure which is of novel character, and which is not liable to derangement.

Another and important object is to provide mechanism peculiarly useful in connection with alternating currents, and designed to prevent excessive chattering due to the frequency thereof while preventing the movable armature member from sticking after the current is cut off from the coil.

An embodiment of the invention that has proven entirely satisfactory, is illustrated in the accompanying drawings, wherein:—

Figure 1 is a side elevation of the device,

Fig. 2 is a top plan view thereof,

Fig. 3 is a vertical sectional view through the apparatus,

Fig. 4 is a horizontal sectional view,

Fig. 5 is a detail view in elevation of the switch mechanism and associated parts, and

Fig. 6 is a reverse view of the parts illustrated in Fig. 5.

Similar reference numerals designate corresponding parts in all the figures of the drawings.

In the embodiment illustrated, a casing is employed, preferably comprising a cylindrical side wall 7 of glass mounted on a base 8, and having a cap 9 of insulating material. The base and cap are connected by tie bolts 10, which serve to hold the casing in assembled condition.

Within the casing, is suspended an electro-magnet 11 of suitable construction, preferably having a tubular core 12 that ties together a lower head 13 and an upper head 14, the coil 15 surrounding the core and being suitably incased, as shown at 16. The head 14 is considerably heavier than the head 13 and is provided with a pair of out-standing ears 17. Upright bolts 18 pass

through the ears and through the cap 9, the heads 19 of the bolts being seated in grooves 20 formed in the under sides of the ears 17, and the stems of said bolts projected well above the cap 9, and being threaded, as 60 illustrated at 21. Binding nuts 22 are screwed upon the threaded ends, so that these bolts constitute binding posts, as will be readily understood. The terminals 23 of the electro-magnet are electrically connected to the bolts 18, so that said binding posts constitute means for attaching leads to the electro-magnet. The head 14 of the electro-magnet is spaced a considerable distance from the cap 9 and for this purpose 70 spacing sleeves 24 are located on the bolts 18 between the ears 17 and the under side of the cap.

The space thus produced between the head 14 and the cap 9 is utilized by an electric 75 switch member. This member, as shown, consists of spaced metallic fingers 25 pivoted, as shown at 26, to heads 27 formed upon the lower ends of binding posts 28 that extend through the cap 9 and project thereabove. These fingers 25 are electrically connected to the heads 27 by suitable yielding strips 28a. The fingers 25 are furthermore connected by a cross bar 29 of insulating material, and said bar has an outstanding ear 30 through which is passed the stem 31 of an armature 32 that is located in the tubular core 12 of the electro-magnet. This armature comprises a fixed upper member 33 of magnetic material through which the 90 stem 31 slidably passes. Carried by the lower end of the stem is a movable plunger element comprising a section 32a of magnetic material, the upper end of which is recessed and co-operates with the lower end 95 of the fixed armature member 33. This section 32a is abutted against a shoulder 33a formed on the stem 31. Screwed upon the lower end of the said stem and therefore carried thereby is a lower section 32 of magnetic material that is hollow to reduce its weight, and interposed between the sections 32 and 32a is a section 32b of non-magnetic material, preferably brass.

The section 32a is proportioned to the 105 member 33, so that enough lines of residual magnetism are allowed to hold the weight of the lower member during the change of current, and while the voltage is at zero, but is small enough so that the two will not 110

stick when the circuit through the coil has been broken. The concave upper end of the member 32^a prevents any accumulation of dust and dirt on the top of the armature, 5 which might cause the same to stick, and the small contact surface will hold better when the coil is energized, and will also break quicker after the current has been cut off from the coil. By this arrangement 10 therefore it is found that chattering is eliminated.

The upper end of the stem 31 carries a flange 34 and a pad 35 which are disposed below the ear 30 of the cross bar 29, thereby 15 constituting an abutment that strikes the under side of said ear, while a washer 36 and clip 37 located on the stem above the ear 30 limits the downward movement of the stem and armature with respect to the bar.

20 Secured to the fingers 25 and extending above and below the free ends of the same, are contact members in the form of leaf springs 38 that have their free ends normally spaced from the free ends of the fingers. Arranged above the upper contact springs 38 are contact elements 39 formed by the lower ends of binding posts 40, and other contact elements 41 are located below the free ends of the lower springs 38, these 30 latter contact elements being carried by brackets 42 supported from the cap 9 by binding posts 43.

With this arrangement, it will be evident 35 that when the electro-magnet is deenergized, the armature 32 will drop, and as a consequence, the switch member will fall, so that the lower contact springs 38 will engage the contact elements 41, and the free ends of the fingers 25 will rest upon the engaged terminals of the springs 38, so as to insure and maintain an electrical contact. On the other hand, when the electro-magnet is energized, the armature 32 will be elevated, thereby 40 raising the switch member and causing the upper set of contact springs 38 to engage the contact elements 39, the free ends of the fingers 25 also engaging these contact springs and insuring a good electrical contact.

45 From the foregoing, it is thought that the construction, operation, and many advantages of the herein described invention will be apparent to those skilled in the art, without further description, and it will be understood that various changes in the size, shape, proportion and minor details of construction may be resorted to without departing from the spirit or sacrificing any of the advantages of the invention.

50 Having thus fully described my invention, what I claim as new and desire to secure by Letters Patent, is:—

1. In a device of the character set forth, the combination with a casing having a cap, 55 of an electro-magnet having a head adjacent

to but spaced from the cap, bolts passing through the head and cap for securing the two together, spacing sleeves loosely mounted on the bolts and interposed between the head and cap, and leads for the magnet engaged with the bolts and located on the underside of the cap. 70

2. In a device of the character set forth, the combination with a casing having a cap, 75 of an electro-magnet having spaced heads, one of which is adjacent to but spaced from the cap, bolts passing through the heads and cap for securing the two together, means on the bolts interposed between the head and cap, an armature receiving sleeve connecting the heads of the electro-magnet, an armature movable in the sleeve, and a device actuated by the armature and located in the space between the head and cap. 80

3. In a device of the character set forth, 85 the combination with spaced swinging arms pivotally mounted at one end and having their other ends free, of a member of insulating material connecting the arms between their ends, spring contact elements 90 connected to the arms and extending alongside the free ends thereof, contact elements with which the spring elements coact, an electro-magnet and an armature operated by the electro-magnet and engaged with 95 the member of insulating material to swing the arms.

4. In an electro-magnet device for use 100 with alternating currents, the combination with a coil, of an armature therein comprising a fixed member and a plunger member 105 movable toward and from the fixed member, one of said members comprising sections of magnetic material, and a section of non-magnetic material interposed between the sections of magnetic material and an actuating device operated by the plunger and securing the sections together. 110

5. In an electro-magnetic device for use 115 with alternating currents, the combination 110 with a coil, of an armature therein comprising a fixed member of magnetic material and a plunger member movable toward and from the fixed member, said plunger member comprising sections of magnetic material 120 and a section of non-magnetic material interposed between the sections of magnetic material, one of the sections of magnetic material operating adjacent to and being attracted by the fixed member and 125 being so proportioned with respect thereto as to hold the plunger against retrograde movement during the change in current and permit the retrograde movement of the plunger when the coil is deenergized. 130

6. In an electro-magnetic device for use 125 with alternating currents, the combination with a coil, of a fixed armature member therein, a stem passing through the fixed member, and a movable armature member 130

comprising a section of magnetic material on the stem coöperating with the fixed member, another section of magnetic material on the stem, and a section of non-magnetic material interposed between said sections of magnetic material, said stem constituting means for securing the sections together.

7. In an electro-magnetic device for use with alternating currents, the combination with a coil, of a fixed armature member therein, a stem passing through the fixed member, and a movable armature member mounted on the stem, said movable member comprising a section of magnetic material coöperating with the fixed member, one of the adjacent faces of the fixed member and section being recessed, another section of magnetic material having a hollow portion, and a section of non-magnetic material interposed between the sections of magnetic material.

8. In an electro-magnetic device for use with alternating currents, the combination with a coil, of a fixed armature member and 25 a plunger armature member in the coil, one of said members comprising sections of

magnetic material and a section of non-magnetic material between said sections, one of the sections of magnetic material directly coacting with the other member and being 30 so proportioned thereto that it will retain its attracted relation with respect to said other member during the change of current, but will be retracted from said position when the current ceases.

9. In an electro-magnetic device for use with alternating currents, the combination with a coil, of a fixed armature member, a stem slideable through said fixed armature member, a movable armature section carried by the end of the stem, a second armature section coöperating with the fixed member and detachably carried by the stem, and a section of non-magnetic material interposed between the two sections and detachably carried by the stem.

In testimony whereof I affix my signature in the presence of two witnesses.

WILL C. NEAHR.
